(57) **CLAIM**

The ornamental design for a self-inflating tire air regulator, as shown and described.

DESCRIPTION

FIG. 1 is a front perspective view of an example of a housing portion of a self-inflating tire air regulator according to the present disclosure;

FIG. 2 is a top view of the example of FIG. 1;

FIG. 3 is a bottom view of the example of FIG. 1;

FIG. 4 is a front view of the example of FIG. 1;

FIG. 5 is a rear view of the example of FIG. 1;

FIG. 6 is a right side view of the example of FIG. 1; and,

FIG. 7 is a left side view of the example of FIG. 1.

The dashed lines form no part of the claimed design.
